HYDRAULIC ACTUATOR WITH INTEGRALLY HOUSED VALVE

David M. Bland, Dallas, and Richard H. Myers, Arlington, Tex., assignors, by mesne assignments, to Ling-Temco-Vought, Inc., Dallas, Tex., a corporation of Delaware

Filed May 31, 1960, Ser. No. 32,687
7 Claims. (Cl. 121—46.5)

This invention relates to hydraulic motors and valves and more particularly to an improved construction or arrangement comprising a hydraulic actuator and valve.

In many applications wherein a hydraulic actuator is employed in conjunction with a remotely controlled valve, prompt and uniformly accurate response of the actuator to a given change in valve setting is vitally essential. Especially where a high-pressure hydraulic system is utilized for supplying fluid to the actuator through the valve, the springiness or compliance of the hydraulic connection between the valve and actuator barrel has been deleterious to prompt and accurate actuator response. Thus, where hydraulic fluid is admitted by a valve through a tube or pipe to the barrel of an actuator which, to operate, must move a large load, the pipe walls tend to undergo an elastic increase in diameter and the column of fluid in the pipe acts as a fluid spring. A certain amount of fluid and time, therefore, is expended in building up the spring-loading in the fluid and pipe until it is of sufficient magnitude to overcome the load which must be moved by the actuator.

To alleviate this and other difficulties, hydraulic servo valves have been mounted directly on the actuators which they control in order to make the hydraulic connections between the valve and the barrel of the actuator as short as possible and thus reduce the springiness of the column of hydraulic fluid. Also, the walls of the passage or passages connecting the barrel and valve have been made rigid and free of springiness by forming them integrally in the relatively thick and rigid material of which the barrel is made. The interests of compactness of installation, etc., also are served where the barrel passages and the necessary conduits connecting the valve with the pressure and return lines of a hydraulic system have been formed integrally in the barrel wall and where the valve is mounted directly on the actuator.

To connect the valve to these passages, an arrangement has been employed wherein a flat face is formed on the barrel, and all the passages open outwardly through respective ports grouped within this flat. A similar, flat face is formed on the valve housing, and in it are grouped the valve ports in such an arrangement that, when the faces are placed together, the valve ports mate with the corresponding ports in the barrel face. The hydraulic connection at each port is sealed with a circular washer or O-ring which surrounds it and is set into the barrel and/or valve face.

The result, as intended, is a short, rigid hydraulic connection between the valve and actuator and a compact, unitary disposition of the hydraulic passages to and from the valve. Several serious disadvantages, however, accrue to the above-described arrangement. The valve is exposed to mechanical and thermal damage. Bolts or the equivalent must be employed for holding the valve face tightly and precisely engaged with the actuator barrel face, and these must be torqued very carefully to obtain and maintain a true fit and thereby ensure proper sealing. The mating surfaces of the valve and barrel must be made to very close tolerances, and this is difficult in the case of flat surfaces. The O-rings employed around each port form face seals, and since the hydraulic pressure exerted

2

on them is radially outward, it stretches and increases the diameter of the O-ring and reduces its cross-section, thus diminishing its effectiveness as a seal. Each O-ring is an external, oil-to-air seal, and any leakage past it is an external leakage.

It is therefore an object of the present invention to provide a combination hydraulic actuator and control valve therefor in which the valve is better protected from mechanical and thermal damages.

10 Another object is to provide a combination valve and actuator in which flat mating surfaces and face seals between the valve and actuator are eliminated and external seals are reduced in number.

15 A further object is to provide a valve and actuator wherein mounting the valve is more quickly and conveniently accomplished and wherein there is lessened likelihood of leakage of hydraulic fluid.

20 Yet another object is to provide a valve and actuator in which the valve housing is integral with the actuator barrel and in which all sealing surfaces are annular and internal to the housing.

25 A still further object is to provide a valve housing integral with an element of a hydraulic actuator and in which, if desired, the valve body may be shrink-fitted into the housing.

Other objects and advantages will be obvious from the specification and claims and from the accompanying drawing illustrative of the invention.

In the drawing:

30 FIGURE 1 is a perspective, partially cut-away view of the actuator, integral housing, and valve assembly;

35 FIGURE 2 is a plan view of one end of the actuator showing the valve housing in longitudinal section as in a plane designated by the line and arrows II—II in FIGURE 1;

FIGURE 3 is a similar view taken in a plane indicated by the line and arrows III—III in FIGURE 1;

40 FIGURE 4 is a view similar to FIGURE 2 and showing the valve assembly in place in the housing; and

45 FIGURE 5 is a view similar to FIGURE 4 and in which the valve assembly is shrink-fitted into the housing.

With initial reference to FIGURE 1, the hydraulic actuator 10 has a barrel 11 formed of a metal or other suitable material which encloses a chamber 12 in which a piston 13 is slidably mounted. A rod 14 which is connected to one face of the piston 13 and which extends outwardly from one end of the barrel 11 causes the piston face to

45 which it is joined to be smaller in area than the opposite face of the piston. In the particular example shown, the smaller face of the piston 13 is continually supplied with hydraulic pressure by a passage 15 which is cast, drilled, or otherwise formed in material integral with the barrel 11 and which has an opening into the chamber 12 at or

50 near its end from which the piston rod 14 emerges. The pressure passage 15 opens to the outer surface of the barrel 11 at, for example, one side of the end of the barrel from which the piston rod 14 extends, and the opening is adapted for connection, with a hydraulic pressure line (not shown) leading to a hydraulic pressure source, by any

55 desired means such as, for example, threading the opening as at 16 to receive a standard hydraulic tube attachment fitting. A branch 17 of the pressure passage 15 is routed through material integral with the barrel 11 to the valve housing 18 and opens into the latter as will be described.

60 A return passage 20 similarly formed in the material of the barrel 11 has an opening which is located as at 19 in the outer surface of the barrel and also is adapted for connection with a line, in this case the return line (not shown) of a hydraulic system. From its opening 19, the return passage 20 leads to the valve housing 18 by a route which, neglecting differences in length, preferably

65

lies opposite and symmetrically matches the path of the pressure passage 17. In addition to the pressure and return passages 17, 20, at least one other passage is integrally formed in the material of the barrel as at 21 (FIGURE 3) and is described in a later paragraph.

The housing 18 is of one-piece construction and is cast or otherwise reduced in one integral piece with the barrel 11. As seen in FIGURE 2, the housing 18 has a cavity 23 which is cylindrical about an axis 22. One end of the cavity 23 preferably is closed either by a portion 24 (FIGURE 5) of the material of which the housing 18 and barrel 11 are made or by closure means such as a transversely extending plate 25 (FIGURE 2) seated against an annular shoulder in the cavity 23 and held in place by a lock ring 26 seated in a groove adjacent the shoulder or by other suitable fastening means. The cavity 23 has an end opening 28 surrounded and defined by a flat face or shoulder 27 of the housing. In the preferred example, this face 27 is surrounded by a cylindrical, internally threaded wall 29 made of the material of the housing 18 and barrel 11 and forming a larger-diameter, open-ended auxiliary cavity 30 coaxial with the valve cavity 23.

With continued reference to FIGURE 2, the pressure and return passages 17, 20 have communication with the valve cavity 23 through respective openings 31, 33 formed in the material of the barrel 11 and housing 18 and leading into the cavity 23. These openings 31, 33 are axially spaced from each other along the cavity axis 22, and between and axially spaced from them is at least one opening 32 which leads, through the at least one other passage 21 (FIGURE 3) previously mentioned, into the barrel chamber 12. The length of this at least one other passage 21 should be kept as short as possible. In the preferred example, one end of the barrel chamber 12 is constantly supplied with hydraulic pressure through the passage branch 15 (FIGURE 1), and the housing 18 is so located axially of the barrel 12 that the opening 32 is in register, as shown in FIGURE 3, with the closed end of the barrel chamber 12. It is of importance that a common wall portion 34 (FIGURE 3) separates the barrel chamber 12 and valve cavity 23 and that the valve cavity opening 32 is located as described, for by connecting the opening 32 into the chamber 12 through the passage 21, which preferably is formed perpendicular to the axis of the barrel cavity, the shortest possible passage for connecting the valve cavity opening 32 to the barrel chamber 12 is provided. The passage 21, accordingly, has the advantage of being very short, and it need have no axial extension at all relative to the barrel chamber 12. It further will be noted that no fittings or seals whatever are required in connecting the barrel chamber 12 to the valve cavity 23 or the pressure and return passages 17, 20 into the valve cavity, and this is a significant advantage in increasing the reliability of operation of the actuator 10 in that a number of potential leak-points are thereby eliminated. The pressure, return, and barrel passages 17, 20, 21 will be understood to constitute means connecting the corresponding cavity openings 31, 33, 32 to the pressure and return lines of a hydraulic system and to the barrel cavity.

With added reference to FIGURE 4, the valve assembly 35 is an electrohydraulic unit with a cylindrical body 36 having an imperforate end wall 37 through which, since it is closed, no leakage can occur. At its other end, the valve body 36 has a shoulder portion 38 and a flat face on which is mounted the valve motor 39 which preferably is of smaller diameter than the shoulder 38. When inserted in the valve cavity 23, the closed end wall 37 of the valve body lies adjacent the plate 25 closing an end of the cavity 23, and the shoulder 38 lies on the housing shoulder 27 and forms a stop means which precisely locates the valve body 36 in a desired position along the axis 22 of the cavity. An externally threaded retainer ring 40 engages the threads of the housing wall

portion 29 and bears against the valve body shoulder 38 to hold it firmly in place against the housing shoulder 27, which closes off the open end of the valve cavity 23. Since it only needs to be slipped into place within the valve cavity 23 and the retainer ring 40 tightened, the valve assembly 35 is quickly and easily mounted and connected to the actuator 10 and hydraulic pressure and return passages 17, 20. Totally enclosed in the valve cavity 23, the valve body 36 is well protected from mechanical damage from blows, etc. The valve housing 18 and actuator barrel 11 form a heat sink and shield for the valve body 36 which protects it from sudden rises in ambient temperature. Protection also is afforded the valve motor 39 by the wall portion 29 forming the auxiliary cavity 30, and the latter is readily enlarged to totally enclose the motor.

The valve body 36 has, in its cylindrical sidewall, the same number of ports as there are openings into the valve cavity; thus, in the particular embodiment shown, the valve body has pressure, return and barrel chamber ports 41, 43, 42 each lying in register, along the axis 22 of the valve cavity 23, with a respective pressure, return, or barrel chamber passage opening 31, 33, or 32 into the valve cavity 23. Each of these ports 41, 42, 43 communicates with the interior of the valve body 36. For each port 41, 42, 43 there preferably is supplied a respective groove 44, 45, or 46 in which the port lies and which extends circumferentially of the valve body 36, the diameter of the latter, in the specific embodiment shown, being slightly less than that of the valve cavity 23. Since the grooves 44, 45, 46 are in register with the valve ports 41, 42, 43 and the latter in register with the housing openings 31, 32, 33, each opening communicates directly with a respective groove 44, 45, 46 and through the latter with a valve port 41, 42, or 43.

On each side of each of the grooves 44, 45, 46 is a seal retainer groove in which is mounted an annular sealing means, such as an O-ring 47, expandable metal ring, or other suitable sealing device made of a resilient material. Each O-ring 47 extends circumferentially of the valve body 36 and is radially compressed between the latter and the wall of the valve cavity 23. An annular seal 47 accordingly is located on each side of each of the openings 31, 32, 33 into the valve cavity 23.

To obviate damage to the O-rings 47 when inserting the valve body 36 into the cavity 23, the cavity openings 31, 32, 33 preferably are located in the bottoms of cavity wall grooves, such as 48 (FIGURE 2) whose corners are chamfered. The O-rings 47 (FIGURE 4) thus do not come into contact, when the valve body 36 is inserted into the housing cavity 23, with any sharp edges which may occur at the openings 31, 32, 33 in the cavity wall.

The grooves in the valve body 36 and housing 18 at the pressure passage opening 31 constitute a chamber which is filled with hydraulic fluid under the relatively steady pressure of a hydraulic pressure source. This chamber is closed at each of its ends by a respective one of the O-rings 47, and the sum of the hydraulic forces on each O-ring 47 is in an axial, not a radial, direction. As a consequence, the ring 47 is not stretched, expanded outwardly, and diminished in its cross-section; instead, it is compressed axially and forced the more tightly into contact with the housing 18 and valve body 36. The same result is obtained at the other O-rings 47 sealing off and isolating the barrel and return openings 32, 33. The valve body 36, accordingly, need not be bolted down for forcing the rings 47 into fluid-tight contact with the valve body 36 and housing 18. In a valve making a flat face seal with an actuator barrel, the hydraulic fluid exerts, at every port, a force strongly urging the separation of the valve and barrel, which force must be resisted by attaching bolts. In the present case, the net force exerted by the hydraulic fluid on the valve body 36, both radially and axially of the housing 18, is zero; therefore, no need

at all exists for fastening means employed to resist hydraulic forces. Since the seal between the valve body 36 and housing 18 is effected by the resilient O-rings 47, it is not critical that the valve body 36 be of a precisely exact diameter, and it may be made to wider tolerances than may be employed where a flat face seal is made between a valve and barrel.

In a valve employing a face sealing arrangement with an actuator, each of the seals employed is an air-to-oil seal, one seal for each way in the valve. It will be appreciated that, in the present construction, there are only two air-to-oil seals, i.e. at the two endmost ones of the O-rings 47. In a four-way valve employing the present construction, accordingly, there are only two air-to-oil seals; the rest are oil-to-oil seals at which leakage, if any should occur, can only be internal of the hydraulic system. Furthermore, the two endmost ones of the O-rings 47 seal hydraulic fluid which is at the relatively steady pressures of the pressure and return sides of the hydraulic system and hence are least likely to experience failure resulting in leakage. The actuator chamber pressure has the greatest fluctuation and is the most predisposed to causing O-ring failure. This pressure is sealed by the ones of the O-rings 47 lying to either side of the barrel chamber port 42 (FIGURE 4) which, as explained, can leak only internally of the hydraulic system.

The valve body 36 contains flow-controlling parts and passages which, under control of an electrical signal supplied to the motor 39, regulate and govern the flow of hydraulic fluid through the pressure passage opening 31, valve body pressure and chamber ports 41, 42, and chamber passage opening 32 into the barrel chamber 12 or, as dictated by a signal received by the motor 39, out of the chamber 12 through the chamber passage opening 32, valve body chamber and return ports 42, 43, and return passage opening 33. Since such valve parts and the electrohydraulic control means and electrical connections therefor are well known and form no part of the present invention, they need not be shown or described herein, for they can readily be provided by one skilled in the art, to whom their form and operation will be well known.

Hydraulic fluid supplied under pressure to the opening 16 of the pressure passage 15 is continually admitted to the smaller-area face of the piston 13 through the passage 15 and to the valve pressure port 41 through the passage branch 17 and opening 31. It will be noted that there is free communication between the port 41 and opening 31 because each opens into the annular chamber enclosed between the O-rings lying on each side of the port 41 and passage opening 31. A hydraulically exerted force therefore is continuously imposed on the piston 13 in a direction urging retraction of the piston rod 14, and hydraulic fluid under pressure is continuously supplied to the valve pressure port 42. Upon energization of the motor 39 for connecting the pressure port 41 internally of the valve with the chamber port 42, fluid flows from the latter and through the passage 21 (FIGURE 3) with opening 32 into the actuator barrel chamber 12 at the larger-area side of the piston 13. Since both faces of the piston 13 thus are supplied with the same pressure, the force applied to the larger-area face of the piston 13 prevails, and the piston rod 14 is extended. Upon energization of the motor 39 for closing off internal communication between the valve pressure and chamber ports 41, 42, the piston is hydraulically locked in position. Energization of the motor 39 for causing connection of the chamber port 42 internally of the valve with the valve return port 43 places the larger face of the piston 13 under the return line pressure of the hydraulic system employed, and (the force exerted on the smaller-area face of the piston being then the greater) the piston is moved to retract the rod 14. The retraction expels fluid from the barrel through the passage 21 (FIGURE 3) with opening 32, valve chamber port 42 and return port 43 (FIGURE 4), return port 33, and return passage 20,

the latter having a terminal opening 19 (FIGURE 1) adapted for connection into the hydraulic system return line. Reference is made, for example, to the U.S. Patents 2,767,689 and 2,625,136 issued on October 23, 1956 and January 13, 1953 to William C. Moog, Jr., which patents show arrangements of valve parts and control means that one skilled in the art will readily employ in the valve assembly 35 for the purposes enumerated above. The drawing accordingly shows only the ports 41, 42, 43 opening into the interior of the valve and providing hydraulic connection with the conventional interior parts of the valve.

In the modification shown in FIGURE 5, the O-rings are omitted from the valve body 36A and the latter is made to a diameter enabling it to be shrink fitted into the valve cavity 23 and providing, after the shrink fitting, a fluid-tight seal effected by the annular sealing means formed by the annular parts of the valve body such as 47A lying on each side of the grooves 44, 45, 46 and the ports 41, 42, 43 therein. When this construction is employed, the annular sealing means 47A are integral with the valve body 36A, and the latter becomes, for practical purposes, one piece with the housing 18 so that O-rings are not needed and problems of wear and deterioration of seals between the valve body 36A and the wall of the housing 18 are entirely eliminated. As shown, the closure plate 25 (FIGURE 2) may be omitted and its place taken by an integral end-wall portion 24 of the housing 18.

While only one embodiment of the invention, together with a modification thereof, has been described in detail herein and shown in the accompanying drawing, it will be evident that various further modifications are possible in the arrangement and construction of the components employed without departing from the scope of the invention.

We claim:

1. In combination;
  - a hydraulic actuator having a piston and a one-piece body of material forming a chamber in which the piston is slidably mounted, said material having an exterior surface;
  - a cylindrical cavity in said material, said cavity having an axis, a closed end, and an open end;
  - passages which lead to the exterior surface of the material and at least one of which opens into the chamber;
  - at least one other passage, all of said passages being integrally formed in said material;
  - a plurality of openings in said material mutually spaced along the axis of and leading into said cavity and each of the passages having communication, through a respective one of the openings, with the cavity;
  - a valve assembly rigidly mounted in the cavity, said assembly having a body with a cylindrical outer surface and further having an imperforate end surface lying within the cavity and axially spaced from the cavity open end;
  - a portion of said body spaced from the end surface and closing off the open end of the cavity;
  - ports in the valve body each located, along the axis of the cavity, in register with a respective one of the openings into the cavity;
  - and annular sealing means extending circumferentially of the valve body between the latter and the wall of the cavity on each side of each of the openings into the cavity.

2. In combination with a hydraulic actuator having a barrel with an exterior surface and an inner chamber and a piston slidably mounted in the chamber;
  - a housing made in one integral piece with said barrel and having a cylindrical cavity with an axis and at least one open end;
  - passages leading to the exterior surface of the barrel and at least one of which opens into the inner chamber of the barrel;

- in addition to said passages, at least one other passage, all said passages being integrally formed in the material of the barrel and housing;
- a plurality of openings in said housing, said openings being spaced along the axis of and leading into the housing cavity and each of the passages having communication through a respective one of the openings with the cavity;
- a valve assembly having a body with a cylindrical outer surface, said body being rigidly mounted in the cavity; ports in the body each located, along the axis of the cavity, in register with a respective one of the openings into the cavity;
- and a plurality of annular sealing means extending circumferentially of the body between the cylindrical outer surface of the latter and the wall of the cavity on each side of each of the openings into the cavity.
3. In combination with a hydraulic actuator of the type having a piston and a barrel with a chamber enclosing the piston and further having a pair of integrally formed passages adapted for connection, respectively, with a hydraulic pressure line and a return line and at least one of the passages communicating with the chamber, the construction comprising:
- a housing made in one integral piece with said barrel and having a cylindrical cavity with an axis and at least one open end;
- an electrohydraulic valve assembly having a cylindrical body rigidly mounted in the cavity and having an end lying within the cavity;
- a plurality of openings in the housing into the cavity, the openings being spaced along the cavity axis and each of the passages having communication through one of the openings with the cavity;
- ports in the valve assembly body each located, along the axis of the cavity, in register with a respective one of the openings into the cavity;
- a plurality of annular sealing means extending circumferentially of the body between the cylindrical outer surface of the latter and the wall of the cavity on each side of each of the openings into the cavity;
- a shoulder on said body disposed in closing relation with the at least one open end of the cavity;
- and means extending across and in closing relation to the cavity adjacent the end of said body lying within the same.
4. The combination claimed in claim 3, said annular sealing means being made of a resilient material.
5. In combination with a hydraulic actuator of the type having a piston and a barrel with a chamber enclosing the piston and further having integrally formed passages adapted for respective connection with hydraulic pressure and return lines and at least one of the passages communicating with the chamber, the construction comprising:
- a housing made in one integral piece with said chamber and having a cylindrical cavity with an axis;
- an electrohydraulic valve assembly having a cylindrical body shrink-fitted into the cavity;
- a plurality of openings in said housing, said openings being spaced along the axis of and leading into the housing cavity and each of the passages having communication through one of the openings with the cavity;
- circumferentially extending, annular grooves in the cylindrical body each located, along the axis of the cavity, in register with a respective one of the openings into the cavity;
- and a port located in each groove and leading into the interior of the cylindrical valve body.
6. In combination with a hydraulic actuator having a barrel portion enclosing a chamber and a piston slidably

- 5 mounted in the chamber, the construction comprising: a housing formed integrally with the barrel and having a cylindrical cavity with an axis;
- a pressure passage and a return passage formed integrally in the barrel and opening into the cavity at respective points spaced apart along the axis of the latter;
- at least one other passage formed integrally in the barrel and opening into the chamber enclosed thereby, said at least one other passage opening into the housing cavity between the points where the pressure and return passages open into the cavity;
- a valve assembly having a body with a cylindrical outer surface rigidly mounted in the housing cavity; ports in the valve body each located, along the axis of the cavity, in register with a respective one of the openings into the cavity;
- and a plurality of resilient, annular sealing rings extending circumferentially of the valve body between the cylindrical outer surface of the latter and the wall of the cavity on each side of each of the openings into the cavity.
7. A barrel enclosing a chamber having an end; a piston slidably mounted in the chamber;
- a valve housing having a cavity with an axis;
- a well portion integral with both the barrel and the housing, said wall portion lying between and isolating, one from the other, the barrel chamber and housing cavity;
- a pair of passages integrally formed in the barrel and housing;
- means for connecting said passages respectively to pressure and return lines of a hydraulic system;
- a pair of openings in the housing into the cavity thereof, said openings being spaced along the axis of the cavity and each providing communication between one of the passages and the cavity;
- a third opening into the cavity spaced between the pair of openings and in register with the end of the chamber;
- a passage extending through said wall portion and connecting the third opening with the chamber;
- a valve assembly body rigidly mounted in the housing cavity;
- ports in the body each located, along the axis of the cavity, in register with a respective one of the openings into the cavity;
- and a plurality of sealing means extending circumferentially of the body between the latter and the housing on each side of each of the openings in the cavity.
